UNITED STATES PATENT OFFICE.

ALFRED H. SMITH, OF CHAPPAQUA, NEW YORK.

COMPARTMENT FREIGHT CAR.

Application filed December 21, 1921. Serial No. 524,034.

To all whom it may concern:

Be it known that I, ALFRED H. SMITH, a citizen of the United States, residing at Chappaqua, in the county of Westchester 5 and State of New York, have invented certain new and useful Improvements in Compartment Freight Cars, of which the following is a specification.

The object of my invention is to provide 10 a carrier having means thereon adapted to hold a plurality of containers placed on the carrier against shifting and rocking while on the carrier.

My invention consists of the combination 15 of a carrier having a platform provided with bulkheads extending vertically therefrom, and a substantial distance above the platform, and means on the carrier positioned between the walls of two adjacent 20 containers adapted to be manipulated to engage the containers and hold them against shifting and rocking.

In the drawings:

Figure 1 is a detail side elevation of the 25 carrier with containers thereon, parts being broken away, parts in section.

Fig. 2 is a top plan view of the same.

The carrier is provided with a platform 1, and with bulkheads 2 extending a substantial 30 distance above the platform 1. The bulkheads 2 are the side walls of the carrier, and the carrier is also provided with similar bulkheads, or walls, at each end thereof, as will be readily understood. The angle iron 35 4 is secured at the top edge of the bulkheads to rigidify said edge, as is usual in car construction.

The carrier is also provided at intervals 40 throughout its length with transverse bulkheads 5 extending from side wall to side wall of the car, but terminating short of the top edge of the other bulkheads. Cams then are pivotally mounted on the side walls of the car, the shaft 7 of the cams passing 45 through the side walls and connected to an operating handle 8, which operating handle is provided with a hasp 9 hinged thereto, which hasp is designed to engage with projection 10 on the side wall of the car, and secured thereto by means of the pin 11, whereby the cams are secured against accidental displacement in their operative position.

For purposes of illustrating my invention, 50 I have shown the cams 6 as being elliptical in shape, but of course, it is understood that

any desired shape of cam may be used so long as the cam is of such construction that it will simultaneously engage the walls of two adjacent compartments or containers. 60

When in the position shown in the drawing, the cam 6 engages the wear plates 8^a on the containers 9^a, thereby holding the containers against shifting relative to each other, and against shifting and rocking on the platform of the carrier, and to assist the cam 6 in this function, I provide the containers with guides 12 which engage the abutments 5 in the zone of the bottom of the container. 70

These guides 12 are provided with a bevel 13 on their lower end, which directs the container, as it is being loaded on to the carrier, to one side of the abutment 5 as will be understood. 75

The containers are also provided with spacing elements 14, which engage the side walls of the carrier to overcome any tendency of the containers to shift transversely of the carrier. 80

In order to release the containers for removal from the carrier, it is only necessary to rock the cam 6 by pulling the lever 8 downwardly to a vertical position.

Changes may be made in the details of 85 construction without departing from the scope of the appended claims.

What I claim is:

1. The combination with a carrier having a platform, bulkheads extending vertically 90 from said platform, containers on said platform back of said bulkheads, of means pivotally mounted on oppositely disposed bulkheads, and in locked position extending from one to the other of juxtaposed 95 walls of two adjacent containers, thereby spacing the containers apart and holding them against shifting and rocking on the platform.

2. The combination with a carrier having 100 a platform, bulkheads extending vertically from said platform, containers on said platform back of said bulkheads, of means pivotally mounted on oppositely disposed bulkheads, and in locked position extending 105 from one to the other of juxtaposed walls of two adjacent containers, thereby spacing the containers apart and holding them against shifting and rocking on the platform, and means outside the bulkheads 110 for operating said spacing elements.

3. The combination with a carrier hav-

- ing side and end walls extending a material distance above the platform of the carrier, and functioning as bulkheads for containers placed on the carrier, of cams pivotally mounted on the side walls of the carrier at intervals throughout the length of the carrier, and positioned within the carrier, means for operating each cam to engage adjacent walls of the two containers.
4. The combination with a carrier having side and end walls extending a material distance above the platform of the carrier, and functioning as bulkheads for containers placed on the carrier, of cams pivotally mounted on the side walls of the carrier at intervals throughout the length of the carrier, and positioned within the carrier, means for operating each cam to engage adjacent walls of the two containers, and wear plates on the containers to be engaged by said cams when in their operative position.
5. The combination with a carrier having side and end walls extending a material distance above the platform of the carrier and functioning as abutments for containers placed on the carrier, of cams positioned within the carrier and pivotally mounted on the side walls throughout the length of the wall, an operating handle secured to each cam to move the cam into engagement with adjacent walls of two containers to hold the containers against shifting on the carrier.
6. The combination with a carrier having side and end walls extending a material distance above the platform of the carrier and functioning as abutments for containers placed on the carrier, of cams positioned within the carrier and pivotally mounted on the side walls throughout the length of the wall, an operating handle secured to each cam to move the cam into engagement with adjacent walls of two containers to hold the

containers against shifting on the carrier, a hasp pivoted to the free end of the handle and means on the side walls to engage the hasp and lock the handle to hold the cams in operative position.

7. The combination with a carrier having side and end walls, transverse bulkheads extending from side wall to side wall of the car, said walls and bulkheads functioning as abutments for containers placed on the car, and means pivotally mounted on the side walls and positioned vertically over the bulkheads and in locked position extending from one to the other of juxtaposed walls of adjacent containers whereby the containers are spaced apart and held against shifting and rocking on the carrier.

8. The combination with a carrier having a platform, abutments extending vertically from said platform, containers on said platform back of said abutments, shafts pivotally mounted on opposite abutments and positioned between adjacent walls of two containers, and means on said shafts adapted to engage juxtaposed walls of two adjacent containers, thereby spacing the containers apart and holding them against shifting and rocking on the platform.

9. The combination with a carrier having a platform, abutments extending vertically from said platform, containers on said platform back of said abutments, shafts pivotally mounted on opposite abutments and positioned between adjacent walls of two containers, and means on said shafts adapted to engage juxtaposed walls of two adjacent containers, thereby spacing the containers apart and holding them against shifting and rocking on the platform, and means outside of the abutments for operating said shafts and means.

In testimony whereof I affix my signature.
ALFRED H. SMITH.
